WINDOW VENTILATOR

Filed July 14, 1928

UNITED STATES PATENT OFFICE.

ELLIS B. DOOLEY, OF TERRE HAUTE, INDIANA.

WINDOW VENTILATOR.

Application filed July 14, 1928. Serial No. 292,768.

This invention relates to ventilators, and the general object of the invention is to provide a window ventilator adapted to be associated with a window in such a manner that 5 when the window is open for ventilation, the air is directed upwardly for proper circulation about a room, thereby preventing drafts.

A further object of the invention is to provide a window ventilator that is adjustable 10 to accommodate air deflecting means of various thicknesses, and includes means to protect air deflecting means against breakage or damage.

Another object of the invention is to provide a window ventilator that is simple in construction, inexpensive to manufacture and install, and is efficient in operation and service.

This invention also consists in certain other 20 features of construction and in the combination and arrangement of the several parts, to be hereinafter fully described, illustrated in the accompanying drawings and specifically pointed out in the appended claims.

25 In describing my invention in detail, reference will be had to the accompanying drawings wherein like characters denote like or corresponding parts throughout the several views, and in which:—

30 Figure 1 is a fragmentary front elevation of a window illustrating the application of the ventilator forming the subject matter of the present invention.

Figure 2 is a sectional view taken approximately 35 on the line 2—2 of Figure 1 looking in the direction of the arrows.

Figure 3 is a sectional view taken approximately on the line 3—3 of Figure 1, looking in the direction of the arrows.

40 Figure 4 is a detail view of one of the members of one of the end brackets.

Figure 5 is a similar view of the other member of one of the end brackets.

Referring to the drawings in detail, the 45 letter A indicates a window frame and the end brackets of my ventilator are adapted to be secured to the confronting inner faces of the frame as best shown in Figure 1 of the drawings.

50 The end brackets each include a pair of members which for distinction are indicated by the reference numerals 1 and 2.

The members are substantially triangle shape and formed with the members 1 adjacent the straight edge thereof is a pair of 55 openings 3 adapted to register with slots 4

formed in the members 2, and these openings or slots receive screws 5 for securing said members in cooperative position to the frame as above set forth. 60

The members 2 are each provided with guide flanges 6 formed with the upper edges thereof for the purpose of receiving the upper edges of the members 1, and formed with each of the members along the inclined edges thereof is a flange 7 disposed at right angles with respect to the body of the members as best shown in Figures 4 and 5 of the drawings. These flanges 7 cooperate for receiving the ends of a deflecting means which 70 as shown is in the form of a plate 8 preferably of glass, but I want it understood that any type of deflecting means may be provided without departing from the spirit of the invention. 75

By providing the slots 4 in the members 2 it will be apparent that these members 2 can be adjusted relative with respect to the members 1 with the result, the flanges 7 can be adjusted accordingly for the purpose of 80 receiving deflecting means of various thicknesses.

The brackets are secured to the window frame in a manner whereby the inclined edges thereof are disposed inwardly, while the 85 straight or outer edges are arranged in a manner so that they will not interfere with the proper operation of the window.

The deflecting means is protected thru the instrumentality of elongated strip 9 transversely rolled upon itself and being provided with an inwardly directed flange 10 cooperating with a straight portion 11 for the purpose of forming a guide to receive the upper edge of the deflecting means, while formed with 95 the lower edge of the straight portion 11 is a horizontal flange 12 that has its ends resting upon the top edges of the members that provide the end brackets. By this construction, it will be apparent that the elongated strip 100 not only protects the deflecting means from breakage or damage, due to the fact that the strip materially strengthens the deflecting means, but the strip provides a convenient rest for the arms of a person when it is desired 105 to stand adjacent the window and look out of the same.

From the above description and disclosure of the drawings, it will be obvious that I have provided a window ventilator that is constructed in a manner whereby it is capable of receiving deflecting means of various thick- 110

nesses, and the deflecting means is protected against damage or breakage. The ventilator can be easily installed and allows for the passage of air through a window so as to properly ventilate a room but eliminate direct drafts.

The apex ends of the members are disposed in contacting engagement with the sill of the window frame with the result the deflecting means will rest upon the sill and incline inwardly into the room as best shown in Figure 2.

It is thought from the foregoing description that the advantages and novel features 15 of my invention will be readily apparent.

I desire it to be understood that I may make changes in the construction, and in the combination and arrangement of the several parts, provided that such changes fall within 20 in the scope of the appended claims.

What is claimed is:—

1. A window ventilator of the character described comprising end brackets each including a pair of substantially triangle shaped members, means for securing said members to the confronting inner faces of a window frame, one of said members of each bracket being movable with respect to the other of said members, flanges formed on the 25 inclined edges of said members, deflecting means received between the flanges of each member, an elongated strip detachably secured to the top of the deflecting means, and means formed with said strip and resting 30 upon the upper edges of one of said members.

2. A window ventilator of the character described comprising end brackets each including a pair of cooperatively associated

members of substantially triangle formation, means for securing said members in cooperative association to the confronting inner faces of a window frame, one of said members of each bracket being adjustable with respect to its companion member, flanges formed with the inclined edges of said members, deflecting means received between said flanges, means detachably received by the upper end of said deflecting means for protecting the latter, and a flange formed with the upper edge of one of said members of each bracket and providing a guide for receiving the other member of each bracket.

3. A window ventilator of the character described comprising end brackets each including companion members of substantially triangle formation, one member of each bracket being provided with openings adapted to register with slots formed in the other member thereof, means for passage through said openings and slots for securing said brackets to the confronting faces of a window frame, flanges formed with the inclined edges of the members and cooperating to provide guides, a flange formed with the upper edge of the slotted members for receiving the upper edge 60 of the other members, a plate received in said guides, an elongated strip including a rounded portion, a straight portion, a flange formed with said strip and cooperating with the straight portion for receiving the upper edge 65 of the plate for clamping engagement therewith, and means formed with the straight portion and being adapted to rest upon the upper edge of the slotted member.

In testimony whereof I affix my signature.
ELLIS B. DOOLEY.
